UNITED STATES PATENT OFFICE.

WALTER GLEN, OF MEADOW CREEK, IDAHO.

BASE FOR POLES.

Application filed February 9, 1923. Serial No. 618,150.

To all whom it may concern:

Be it known that WALTER GLEN, a citizen of the United States of America, residing at Meadow Creek, in the county of Boundary 5 and State of Idaho, has invented new and useful Improvements in Bases for Poles, of which the following is a specification.

The object of the invention is to provide a relatively simple and inexpensive base of durable construction for telegraph and telephone poles and similar service poles such as those used for electric power conductors and lines, and particularly to provide a substantial base for the purpose indicated 10 which may be constructed on the ground or at the point of use to avoid the expense of transportation; and with these objects in view the invention consists in a construction and combination of parts of which a preferred embodiment is shown in the accompanying drawings, wherein:—

Figure 1 is a side view, and

Figure 2 is a sectional view of a pole base embodying the invention as seen when set in 25 the ground ready for use.

Figure 3 is a plan view thereof.

The device consists essentially of a block 10 of concrete or cement having a socket 11 for the reception of the lower end of the 30 pole 12 and preferably tapered slightly toward its lower end, and a cap 13 removably fitted on the upper end of the cap in embracing relation with the pole and serving as a means of locking the pole to the block, 35 the block being provided interiorly and in communication with the socket thereof with a pocket or reservoir 14 for a wood preservative preparation or compound such as a tar preservative, for the protection of 40 the lower end of the pole from the effects of insects, moisture and the like.

The cap is preferably of sectional construction having the semi-circular members 13^a and 13^b drawn upward to form a neck 45 15 which may be engaged as indicated in the drawing by a clamp 16 adjustable by means of a suitable bolt 17 or its equivalent to tightly clasp the neck and insure a close contact and engagement of the inner surface 50 thereof with the surface of the pole. Attached to suitable anchors 18 which are em-

bedded in the block are bolts 19 extending upward to a sufficient distance above the upper end of the block to engage slots 20 formed in the members of the cap, and fitted 55 with nuts 21 for holding the cap in position on the block and thereby locking the pole in place in the block.

A base constructed as herein described and preferably extending at its upper end 60 slightly above the surface of the ground, indicated by the ground line 22 in the drawing, serves to protect the lower end of the pole against moisture which in the form of rain is shed by the upper surface by the 65 cap, and while the pole is free to bend or yield under the stress of wind the working of the lower end thereof is prevented and therefore looseness and the tendency to break or be thrown down is reduced to the 70 minimum. Obviously the socket in the base may be made of such a depth as to insure a firm seating of the pole and may be varied to suit those localities in which high 75 winds are prevalent.

Having described the invention, what is claimed as new and useful is:—

1. A base for telegraph and similar poles having a block adapted to be embedded in the ground and provided with a socket for the reception of the lower end of the pole, a cap for clamping and snugly fitting the pole in surmounting relation with the block, and means for securing the cap to the block, said cap consisting of separable sections and 80 being provided with an upwardly directed 85 reduced neck engaged by an encircling clamp.

2. A base for telegraph and similar poles having a block adapted to be embedded in the ground and provided with a socket for the reception of the lower end of the pole, a cap for clamping and snugly fitting the pole in surmounting relation with the block, and bolts for securing the cap to the block, 90 the cap being composed of separable sections having slots for the reception of said 95 securing bolts.

In testimony whereof he affixes his signature.

WALTER GLEN.
